UNITED STATES PATENT OFFICE.

GEORGE J. FORCIER, OF CLEVELAND, OHIO.

CLEANING DEVICE.

Application filed August 4, 1922. Serial No. 579,653.

To all whom it may concern:

Be it known that I, GEORGE J. FORCIER, a citizen of the United States, residing at Cleveland, in the county of Cuyahoga and State of Ohio, have invented certain new and useful Improvements in Cleaning Devices, of which the following is a specification.

This invention relates to cleaning devices and is particularly adaptable for cleaning wall paper and the like. The device consists generally of a threaded rod mounted upon the upper end of a handle and carrying a hinged cross-bar and two rolls something below the cross-bar. The cross-bar carries a brush or felt pad which is saturated with a chemical solution. A cloth is wound from a roll over the cross-bar and brush carried thereby and on to the other roll, the cloth being saturated with the chemical cleansing solution as it passes over the saturated pad or brush. The cloth then is rubbed along the wall paper thus cleansing it.

In the drawings Fig. 1 is a front elevation of the device. Fig. 2 is a side elevation thereof. Fig. 3 a central vertical section on the line 3—3 of Fig. 1, and Fig. 4 is a detail sectional view showing a slight modification.

Referring to the drawings by reference numerals 1 indicates the threaded rod, which is mounted on the upper end of a handle 2. The rod 1 carries brackets 3 and 4, projecting on opposite sides of the rod, the bracket 4 being somewhat below bracket 3. These brackets carry rolls 5 and 6 therein on which a cloth indicated in dot and dashed line at 7 in Fig. 2 is wound.

A cross-piece indicated generally by 8 consists of two middle sections 9 and 10 which are hinged together as indicated at 11, and the adjacent ends of the sections 9 and 10 are beveled as shown at 12. The hinge 11 is supported in a bracket 13 on the upper end of a post 14 which extends downwardly through a hole 15 in the top of a cap 16 which is screwed on to the upper end of rod 1, and into rod 1. The cap 16 can be screwed up or down on the rod 1 and will contact with the beveled faces 12 of the sections 9 and 10 and will keep them in a position shown in Fig. 1, or if the cap 16 is screwed downwardly it will allow the sections 9 and 10 to swing downwardly about the hinge 11. Sections 9 and 10 each has hinged thereto at 17 an extension 18. Rods 19 have one end pivoted at 20 to the outer ends of the sections 18 and

the other end pivoted at 21 to a ring 22 which works in a groove 23 in an internally threaded sleeve 24 which is adapted to be screwed up and down the rod 1 to raise or lower the sections 18 as indicated by the dotted lines in Fig. 1.

The end 26 of the roll 6 has a ratchet 27 thereon which is adapted to be engaged by a pawl 28 carried by an arm 29 which swings around the pivot 30 of the roll 6. A cord 31 is attached to the arm 29 and passed through an eye 32 and then across and through another eye 33 and then downwardly along the handle 2 where it can be grasped by the operator. A spring 34 has one end attached to bracket 4 and the other end attached to the lower end of arm 9 and will return the pawl after it has been operated by the spring 1. The end face 34 of the roll 5 has depressions 36 therein which are engaged by a depression 37 in an arm of the bracket 3 and will prevent the roll 5 from turning unless the ratchet mechanism is operated.

The bar 8 has a groove 39 therein on which the pad or brush 40 is secured. Bar 8 also has rods 41 and 42 attached thereto, these rods being pivoted at 43, 44 and 45, these pivots being in line with hinges 11 and 17. The cloth 7 is then fed from the roll 5 under one of the rods 42 over the brush 40 and under the other rod 41 and on to the roll 6.

In Fig. 4 a slight modification is shown which can be used in place of the sleeve 24. In this form the rod 1^a is not threaded but has a series of notches 1^b therein and a sleeve 24^a has a smooth interior and is notched as shown in 24^b and has a spring 95 dog 24^c attached thereto at 24^d and extending in through the notch 24^b in the sleeve 24^a and engaging one of the notches 1^b in the rod 1^a. The rods 19 are pivoted to sleeve 24^a as indicated at 21^a.

I claim:

1. A cleaner comprising a handle rod having a cross bar at the end, a roll at each side of the rod, a cloth wound on the rolls and extending over the cross bar, and means to wind the cloth from one roll to the other, the cross bar being provided with a pad of absorbent material over which the cloth runs to saturate the latter with a cleaning agent carried by the pad.

2. A cleaner comprising a handle rod having a cross bar at the end, a roll at each side

of the rod, a cloth wound on the rolls and extending over the cross bar, and means to wind the cloth from one roll to the other, the cross bar consisting of sections hinged together, and means carried by the handle to operate the hinged sections.

3. A cleaner comprising a handle rod having a cross bar at the end, a roll at each side of the rod, a cloth wound on the rolls and extending over the cross bar, and means to wind the cloth from one roll to the other, the cross bar consisting of sections hinged together, and means carried by the handle to operate the hinged sections, said means including rods connected to the hinged sections and a sleeve connected to said rods and movable back and forth on the handle rod.

10 4. A cleaner comprising a handle rod, a cross

bar fixed to the head end thereof and provided with a groove, an absorbent pad in said groove, a pair of rolls carried at opposite sides of the rod, and a cloth wound on said rolls and extending over the pad.

5. In a cleaner the combination of a cloth, means to press the same against a surface to be cleaned, means to move the cloth while so pressed against said surface, and means to supply the cloth with a cleaning solution as it passes over said surface.

15 In testimony whereof, I affix my signature in presence of two witnesses.

GEORGE J. FORCIER.

Witnesses:

JOHN A. BOMMHARDT,
BESSIE F. POLLOK.
